(57) **CLAIM**

The ornamental design for a bottle, as shown and described.

DESCRIPTION

FIG. 1 is a front perspective view of a bottle in accordance with my preferred design;

FIG. 2 is a rear perspective view thereof;

FIG. 3 is a front elevation view thereof;

FIG. 4 is a left side elevation view thereof;

FIG. 5 is a rear elevation view thereof;

FIG. 6 is a right side elevation view thereof;

FIG. 7 is a top plan view thereof;

FIG. 8 is a bottom plan view thereof;

FIG. 9 is a front perspective view of a bottle in accordance with a second embodiment of my design;

FIG. 10 is a rear perspective view of the bottle in accordance with the second embodiment of my design;

FIG. 11 is a front elevation view of the bottle in accordance with the second embodiment of my design;

FIG. 12 is a left side elevation view of the bottle in accordance with the second embodiment of my design;

FIG. 13 is a rear elevation view of the bottle in accordance with the second embodiment of my design;

FIG. 14 is a right side elevation view of the bottle in accordance with the second embodiment of my design;

FIG. 15 is a top plan view of the bottle in accordance with the second embodiment of my design; and,

FIG. 16 is a bottom plan view of the bottle in accordance with the second embodiment of my design.

The broken lines in the drawings showing the bottle illustrate the portions of the bottle that form no part of the claim. The shaded surfaces adjacent the broken lines in FIGS. 9-14 represent the bounds of the claim.

1 Claim, 8 Drawing Sheets
